UNITED STATES PATENT OFFICE.

PHILIPP KNORPP AND GUSTAVE A. MAYER, OF STAPLETON, NEW YORK.

DESIGN FOR A CHRISTMAS-TREE ORNAMENT.

SPECIFICATION forming part of Design No. 18,238, dated April 3, 1888.

Application filed February 6, 1888. Serial No. 263,183. Term of patent 3½ years.

To all whom it may concern:

Be it known that we, PHILIPP KNORPP and GUSTAVE A. MAYER, of Stapleton, in the county of Richmond and State of New York, have invented a new and original Design for Christmas-Tree Ornaments, of which the following is a specification.

In the accompanying drawing a face view of our new design for Christmas-tree ornaments is shown.

The leading feature of our new design for Christmas-tree ornaments consists of a tapered body, shoulders or offsets at the wider end of the same, a slightly-flaring head on the wider end, a representation of a face on said head, depressed cross-lines on the body, and circular depressions in the panels produced by the crossed lines.

A is the tapered body; B, the shoulders at the wider end of the same; C, the flaring head on the wider end of the body; C', the representation of the face; D, the crossed depressed lines, and E the depressed ornaments in the panels produced by the depressed crossed lines.

Having thus described our design, we claim as new and desire to secure by Letters Patent—

The design for a Christmas tree ornament, consisting of the tapered body A, the shoulders B, the flared head C, the representation of a face on said head, the depressed cross-lines D, the circular depressions E, and the panels on the body, both side edges having the same contour, substantially as herein shown and described.

In testimony that we claim the foregoing as our invention we have signed our names in presence of two subscribing witnesses.

PHILIPP KNORPP.
GUSTAVE A. MAYER.

Witnesses:

PAUL GOEPEL,
JOHN A. STRALEY.
